CLAIM

The ornamental design for a shoelace, as shown and described.

DESCRIPTION

FIG. 1 is a perspective top view of a shoelace, showing my new design;

FIG. 2 is a front view thereof in one position; and,

FIG. 3 is a front view thereof in a second position.

The dashed seam edge lines shown on the shoelace depict stitching, which forms no part of the claimed design. The broken lines in FIGS. 1-3 depict environmental features that form no part of the claimed design.
